FEED MECHANISM OF MACHINE AND LIKE
AUTOMATIC GUNS

Josef Dobremysl, Cambridge, England

Application March 4, 1941, Serial No. 381,654
In Great Britain November 9, 1939

2 Claims.

(Cl. 89—33)

This invention relates to feed mechanism of machine and like automatic guns of the kind in which the cartridges are fed successively into the loading position by means of a belt and in which the belt is moved by means of one or more feeding pawls and held in position by means of one or more retaining pawls, mounted above and below the belt respectively or vice versa.

It happens sometimes that the feed mechanism becomes jammed or inoperative and apart from the exigency of the moment it is imperative for other reasons for the mechanism to be released as quickly as possible, one important reason being the risk of premature explosion of the cartridge when the barrel is hot.

In the absence of some other provisions for releasing the belt it is necessary to open the cover of the breech and to disengage the pawls by hand. This method besides being highly dangerous is also slow and inconvenient.

I am aware, however, that it has already been proposed to provide for the release of the pawls by means of pins or press buttons. This arrangement has the disadvantage that it is very difficult, and in the case of guns of large calibre, quite impossible to operate both push buttons or pins simultaneously by one hand.

I am aware, however, that in guns of a certain type it has already been proposed to provide for the release of the pawls by means of a single lever release device in which a spindle rotatably mounted in the feed block and having cams adapted to act on feeding and retaining pawls arranged below the cartridge belt, is operated by a lever or trigger. This single lever release device, for both sets of pawls is mounted at a fixed position on the gun, but the disadvantage of this arrangement is that the device engages the feeding pawl only in its final position when it has completed the feeding operation; in all other positions the feeding pawl is out of engagement with the release device so that if it is necessary to release the belt in some intermediate position on the feed path the release device is useless.

The object of the invention is to enable the operation of releasing the belt to be carried out in any position which the feeding mechanism may assume during its operation and to facilitate such operation.

In feed mechanism of the kind herein referred to for machine and like automatic guns, embodying this invention, there is associated with the feeding and retaining pawls, means whereby both pawls can be simultaneously released from engagement with the cartridge belt in any position

which the feeding mechanism may assume during operation.

According to the invention the feeding pawl is provided with an inclined surface adapted for co-operation with a complementary surface on or operated by a releasing device, said complementary surface having a width or being movable so as to cover the whole range of the path of the feeding pawl, and the retaining pawl is provided with an inclined surface or is in operative connection with an organ operated by an inclined surface on the releasing device for the feeding pawl.

The releasing organ for the retaining pawl may be formed as a slideable rod or the like, having an orifice, a slot or a cut out portion, provided with an inclined side wall, said rod being subjected at one side to the action of a lever arm firmly connected with the releasing organ for the other pawl, and on the other side to the action of a spring, urging the rod in the direction towards the arm of the lever.

The tooth of the releasing organ for the feeding pawl has its working incline of such width that it positively engages the inclined surface of the feeding pawl in any point of its feeding path.

The rocking movement of the tooth of the releasing organ for the feeding pawl may be limited, preferably by an abutment which is movable together with the feeding carriage. In a preferred embodiment of the invention this abutment is formed by the wall of a groove which serves to impart driving movement to the feeding carriage.

The two releasing organs for the retaining and feeding pawls respectively may be actuated by a single control member.

In a further embodiment in which the feeding carriage is mounted in the cover of the gun the feeding pawl is provided with an incline co-operating with a corresponding incline on a slide shiftable by the releasing lever, said lever being provided with a tooth depressing a transmitting member or rod, which actuates a cam mounted on the shaft of the retaining pawl.

The accompanying drawings represent by way of example two embodiments of the invention.

Figure 1 shows in front view and partially in section a part of the feeding device of an automatic gun provided with a releasing device according to the invention.

Figure 2 is the respective plan view from which the retaining pawl and the cover have been omitted for better understanding.

Figure 3 shows the releasing mechanism for the feeding pawl in a diagrammatic side view.

Fig. 4 shows in a diagrammatic plan view the retaining pawl of the cartridge feeding device and the single actuating lever of the releasing device with the transmission elements between the retaining pawl and the actuating lever.

Fig. 5 is a sectional side view of the device illustrated in Fig. 4.

Fig. 6 is a view of a further modification of the invention.

The cartridge belt 1 is fed into the gun by a feeding pawl 2, having a lower part 2a. The pawl 2 is rotatably mounted on the bolt 3 in the feeding carriage 4. The cartridges are held in position by a retaining pawl 5, mounted on a bolt 6 which is fixed in the cover 7 of the gun. The pawls 2 and 5 are pressed by their respective springs 8 and 9 into engagement with the belt 1, or with the cartridges.

The belt can be readily released when required by rocking the two pawls 2 and 5 out of engagement therewith. The feeding pawl 2 has an incline 30 on its lower end, as shown in Figure 3. The incline 30 is in engagement with an incline 31 of the tooth 10, which is rigidly mounted on the bolt 11. The width of the tooth 10 is such to make the tooth positively engage the lower end of the pawl 2 at any point of its movement.

The bolt 11 is rotatably mounted in a bearing 12 fixed on the gun. A handle 13, extending on its other end into a lever arm 14 is secured to the upper end of the bolt 11. A rod 15, see Figures 4 and 5, is positioned in the path of the lever arm 14. The rod 15 has a cut out portion 16 (Figs. 4 and 5) into which the part 40 of the retaining pawl 5 extends. The cut out portion 16 has an inclined wall 41 (Fig. 5) capable of cooperating with the incline 42 (Fig. 5) of the part 40 of the retaining pawl 5. A spring 17 is arranged on the other side of the rod 15, pressing the rod towards the lever arm 14.

During normal operation of the gun the tooth 10 is out of the path of the end of the pawl 2, and the incline is out of engagement with the pawl 5. In order to release the belt, the handle 13 is swung in the direction of the arrows shown in Figures 2 and 4. As a result of this movement the tooth 10 penetrates under the rear end of the pawl 2 and swings the pawl counterclockwise out of engagement with the belt 1. This swinging movement of the pawl 2 is positively accomplished in any position which the pawl 2 may assume on its feeding path, because the tooth 10 is always rocked as far as to bring the pawl 2 to the completely rocked position. In this position the tooth strikes an abutment 18 (Fig. 2) forming a part of a feeding carriage of known construction and movable with it. In the example shown in Figs. 1 and 2 the abutment 18 is formed by the wall 18 of the driving groove 45 (Fig. 2) of said feeding carriage. In this groove 45 known means are arranged for imparting the feeding movement to the feeding carriage. The operator swings the handle 13 as far as the abutment 18 allows.

Simultaneously with the handle 13 the lever arm 14 also swings out and presses the rod 15 in the direction of the arrow, in Figure 4. The incline of the slot 16 in the rod 15 presses down the rear end of the pawl 5, so that the pawl 5 swings out of the path of the belt, into the position represented in dotted lines in Figure 1. In this way the belt is entirely released and may be pulled out of the gun. The handle 13 may then be brought back to the original position, thus causing the

pawls 2 and 5 to slide down from the respective inclines and return to their operative positions under the influence of their respective springs.

It can be seen from the foregoing that according to the invention only one operation is required to release the belt 1, namely, by the rocking of the handle 13. The handle 13 being mounted in the bearing 12, remains in the same position on the gun and the operator does not need to look for it, as is necessary in certain kinds of firearms, where one of the buttons to be pressed, in order to release the belt, changes its position together with the feeding carriage. Any opening of the cover or removal of any other part of the gun is entirely avoided.

It is obvious that the device according to the invention may be used for feeding mechanisms operating from either side of the gun.

It is also obvious that the releasing organ of the retaining pawl 5 need not be formed by a separate rod 15. The lever arm 14 may be provided with an extension or shaped in such a way to depress said retaining pawl when swung into operative position.

Figure 6 represents another embodiment of the invention as applied to a gun of a type in which the feeding carriage is arranged in the cover.

The cartridge belt consisting of links 20 is fed into the gun by a feeding pawl 21, mounted on and movable with the feeding carriage (not shown) and is retained in its position by a retaining pawl 22. The feeding pawl is provided with an inclined surface 23, co-operating with a corresponding inclined surface on a slide 24. The slide 24 may be moved against the incline 23 by a lever 25, pivotally mounted at 26 on the gun (not shown).

The shaft of the retaining pawl is provided with a finger or cam 27 co-operating with a rod 28, the upper end of which co-operates with an inclined surface or tooth 29 on the lever 25.

The belt can be instantly released when required or necessary by rocking the lever 25 in the direction of the arrow A. By this movement the slide 24 is shifted against the incline 23, thus rocking the feeding pawl 21 out of engagement with the link 20, as indicated by the arrows in Figure 6. At the same time the tooth 29 depresses the rod 28 which in turn rotates the cam 27, and, by the intermediary of the shaft, the retaining pawl in the direction of the arrow, leaving the belt free for removal from the gun.

I claim:

1. An automatic gun having a frame, a feeding carriage slidably in said frame, a feeding pawl movable with and pivotally mounted on said carriage for engagement with a cartridge belt, a retaining pawl pivotally mounted on said frame for engagement with said cartridge belt, a first arm rigidly connected to said feeding pawl and pivotally movable therewith, a second arm having a surface inclined at an acute angle to the pivotal axis of and connected rigidly to said retaining pawl, an actuating lever pivotally mounted on said frame having two lever arms thereon, a slide member slidably mounted on said frame having an inclined portion disposed adjacent the inclined surface of said second arm, means biasing said slide member toward one of said two lever arms, motion transmitting means interposed between the other of said two lever arms and said first arm, said actuating lever being movable to actuate said slide member and said motion transmitting means to rock said retaining pawl by engagement of said inclined portion with said in-

clined surface, and to rock said feeding pawl by engagement of said motion transmitting means and said first arm, respectively.

2. An automatic gun having a frame, a feeding carriage slidable in said frame, a feeding pawl movable with and pivotally mounted on said carriage for engagement with a cartridge belt, a retaining pawl pivotally mounted on said frame for engagement with said cartridge belt, a first arm rigidly connected to said feeding pawl and pivotally movable therewith, a second arm connected rigidly to said retaining pawl and having a surface inclined at an acute angle to the pivotal axis of said retaining pawl, an actuating lever pivotally mounted on said frame having two lever arms thereon, a slide member slidably mounted on said frame having an inclined portion substan-

tially complementary to and disposed adjacent the inclined surface of said second arm on said retaining pawl, means biasing said slide member toward one of said two lever arms, and an inclined cam portion on the other of said two lever arms, said inclined cam portion being normally disposed adjacent to but in spaced relation to said first arm, said actuating lever being movable to engage said inclined cam with and rock said first arm to disengage said feeding pawl from said cartridge belt, and engage said one of said lever arms with and shift said slide to engage said inclined portion thereon with said inclined surface on said second arm and disengage said retaining pawl from said cartridge belt.
